UNITED STATES PATENT OFFICE

GEORGE R. EATON, OF PUEBLO, COLORADO

DISPLAY DEVICE

Application filed July 3, 1930. Serial No. 465,733.

This invention relates to improvements in display devices of the type employed on counters in stores for the display of goods, and has reference more particularly to a display device for use in displaying neckties.

In order to display goods to the best advantage it is necessary to have proper display devices to which the goods can be attached and which enable the merchant to quickly and conveniently show the different styles and different patterns that he has for sale and this is especially true in connection with neckwear, such as bow ties and similar articles.

It is the object of this invention to produce a simple display device that can be constructed at a nominal cost and which will have an ornamental appearance and at the same time be convenient for the purpose of applying the goods in place thereon and for displaying the same.

This invention briefly described consists of a base which is provided at its ends with two vertical supports. An axle is attached to the supports and carries a hollow cylindrical member of sheet metal that is freely rotatable on the axle. The cylindrical member is provided intermediate its ends with a row of angularly spaced openings and is preferably provided at its ends with a corresponding number of notches or recesses. The material instead of being entirely removed where the openings and the notches are provided, is bent reversely so as to form projections that are spaced a short distance from the outer surface of the cylinder and which are adapted to hold display cards. Neckties are secured to the cylinder by having the neck band pass through these central openings and through the corresponding notches at the end.

Having thus briefly described the invention, the same will now be described in detail, and for this purpose reference will be had to the accompanying drawings in which the preferred embodiment of the invention has been illustrated, and in which:

Fig. 1 is a side elevation of my improved display device, parts being broken away to better disclose the construction;

Fig. 2 is a section taken on line 2—2, Fig. 1; and

Fig. 3 is a section taken on line 3—3, Fig. 2.

In the drawings reference numeral 1 represents the base which may be a piece of board or some other similar material and 2 represents the end supporting members that are secured to the base by means of screws 3. Members 2 are preferably formed from sheet metal of substantially rectangular shape, and their outer surfaces can be used for the display of advertising matter. An axle 4 extends between the two supports and mounted for rotation on this axle is a cylindrical member 5. This member is preferably made from sheet metal and is provided at opposite ends with a spider having four spokes 6 secured to a central hub portion 7. These hub portions are rotatably mounted on the shaft and the ends of the spokes are secured to the cylinder by means of rivets 8, or they may be soldered thereto. The cylinder is provided along its center with a number of rectangular openings 9 that are spaced equiangular distances from each other. These openings are made by cutting the material on two sides and then cutting the central portion into two equal lengths 75 and bending them in opposite directions so as to form hooks 10, as shown in Figs. 1 and 3. The ends of the cylinder are provided with notches 11 that correspond in number and position with the central openings 9 and are so located that one opening and two notches form a straight line as shown in the drawing. The notches are formed by cutting a portion of the material on two sides and then bending these portions inwardly so as to form hooks 12. Hooks 10 and 12 form spaced pairs that are adapted to hold a display card like that indicated by reference numeral 13 in Fig. 3. The bow ties 14 may either be secured to cards which are held in place by means of the lugs in the manner described or the neck band 15 may be passed through one of the openings 9 and through a corresponding notch 11 as shown in the lefthand portion of Fig. 3. Since the end supports 2 do not extend more than a short distance above the center of the cylinder, the inside of the cylinder is accessible for the purpose of placing the bolts thereon and for the purpose of removing them therefrom. A larger number

of notches and openings can be provided than shown in the drawings so that a larger number of ties can be displayed on the same sized cylinder, but for the purpose of explaining 5 the invention, a smaller number of openings has been shown than is actually used.

After the ties have been put in place, the cylinder can be freely rotated so that the customer can inspect all the ties thereon without 10 the necessity of handling any of them. By means of this simple display device, ties and other articles can be displayed to good advantage and they can be kept in better shape and kept cleaner than when they must be handled every time that a customer desires to inspect them.

The cylinder is preferably made from metal but can also be made from any other sheet materials such as fiber or paper, as well as 20 from celluloid or hard rubber. The notches 11 at the ends of the cylinder may be dispensed with and if these are dispensed with the hooks 10 and 12 may also be dispensed with but the preferred construction is the one 25 shown in the drawings.

From the above description it will be apparent that I have produced a simple and inexpensive device, to which bow ties and similar objects can be easily attached and 30 which is a great convenience in the handling of these articles in stores and other places.

Having described the invention what is claimed as new is:

1. A display device comprising, in combination, a base, two spaced vertical supports carried by the base, an axle secured at its ends to the support, a hollow cylinder of thin sheet material supported by the axle and adapted to rotate thereabout, the cylinder 40 having a row of spaced openings extending around its circumference at a point intermediate its ends, the ends of the cylinder being provided with notches that correspond in number and position with the openings in the 45 cylinder.

2. A display device comprising, in combination, a base, two spaced vertical supports carried thereon, an axle secured at its ends to the supports, a cylinder mounted for rotation about the axle, the cylinder having a row or equiangularly spaced openings about its center and a corresponding number of notches in each end, the adjacent edges of the central holes and notches being bent towards 55 each other so as to form grooves for the reception of cards carrying articles of merchandise.

In testimony whereof I affix my signature.
GEORGE R. EATON.
